and a sufficient number of steps and to be positioned in such manner that each subsequent step and each subsequent forward movement of the tractor will cause the loader to be moved forward and upward in a manner to effect a continuous and gradual increase in the height of the raised condition.

2,349,335

UNITED STATES PATENT OFFICE

TRACTOR-CARRIED LOADING APPARATUS

Curtis C. Baldwin, Ottawa, Kans., assignor, by direct and mesne assignments, to C. Earl Hovey, trustee, Kansas City, Mo.

Application October 23, 1942, Serial No. 463,073

4 Claims. (Cl. 214—141)

This invention relates to loaders and more particularly to a loading attachment of the character designed to be mounted on a conventional tractor and to be operated by hydraulic mechanism forming a part of the tractor.

The principal object of this invention is to provide a power loader so constructed that when in lowered condition it is positioned immediately in front of a tractor, whereby maximum lifting power can be applied to the loader on the initial lifting movement, and the pushing action of the tractor can be exerted directly against the loader to eliminate the necessity of extensive bracing of the loading mechanism.

A further object is to embody means in apparatus of this character whereby the loader is extended as it approaches its upper limit of travel, thus increasing the height to which loads may be elevated and allowing such loads to be dumped a substantial distance ahead of the tractor.

Another aim of this invention is to provide a loader having a low over-all height in order to clear low ceilings, doorways and the like.

It is a further aim of this invention to provide a loading attachment of comparatively simple but rugged construction that can be mounted on a tractor of conventional design without requiring extensive alterations of the tractor unit.

Further objects will appear during the course of the following specification, referring to the accompanying drawings wherein:

Fig. 1 is a side elevational view of a loader mounted on a conventional tractor, the raised position of the loader being shown in dotted lines.

Fig. 2 is a side elevational view of the outer end of the loader in raised condition, the dotted lines indicating the dumping position of the loading fingers.

Fig. 3 is a top plan view of a tractor equipped with a loading attachment constructed in accordance with this invention.

Fig. 4 is an enlarged vertical section taken on line IV—IV of Fig. 1, illustrating particularly a depending section of the loader; and

Fig. 5 is a vertical section taken on line V—V of Fig. 4, showing mechanism for latching the loading fingers to one section of the loader.

The numeral 10 designates generally a tractor having front wheels 12 and rear wheels 14, mounted on front and rear axles 16 and 18 respectively. An engine 20 operates a hydraulic pump, forming standard equipment of some tractors and indicated at 22 by dotted lines, although it is obvious that a pump of like character may be driven from any other suitable source.

An auxiliary frame carried by the tractor comprises a pair of spaced parallel members 24

2,349,335

and 26 which are connected to the front and rear axles 16 and 18 by means of brackets 28 and 30.

Brackets 28 and 30 carry frame members 32 and 34 which are connected to the front and rear axles 16 and 18 by means of brackets 36 and 38.

Frame members 32 and 34 are connected to the front and rear axles 16 and 18 by means of brackets 40 and 42.

Frame members 32 and 34 are connected to the front and rear axles 16 and 18 by means of brackets 44 and 46.

Frame members 32 and 34 are connected to the front and rear axles 16 and 18 by means of brackets 48 and 50.

Frame members 32 and 34 are connected to the front and rear axles 16 and 18 by means of brackets 52 and 54.

Frame members 32 and 34 are connected to the front and rear axles 16 and 18 by means of brackets 56 and 58.

Frame members 32 and 34 are connected to the front and rear axles 16 and 18 by means of brackets 60 and 62.

Frame members 32 and 34 are connected to the front and rear axles 16 and 18 by means of brackets 64 and 66.

Frame members 32 and 34 are connected to the front and rear axles 16 and 18 by means of brackets 68 and 70.

Frame members 32 and 34 are connected to the front and rear axles 16 and 18 by means of brackets 72 and 74.

Frame members 32 and 34 are connected to the front and rear axles 16 and 18 by means of brackets 76 and 78.

Frame members 32 and 34 are connected to the front and rear axles 16 and 18 by means of brackets 80 and 82.

Frame members 32 and 34 are connected to the front and rear axles 16 and 18 by means of brackets 84 and 86.

Frame members 32 and 34 are connected to the front and rear axles 16 and 18 by means of brackets 88 and 90.

Frame members 32 and 34 are connected to the front and rear axles 16 and 18 by means of brackets 92 and 94.

Frame members 32 and 34 are connected to the front and rear axles 16 and 18 by means of brackets 96 and 98.

Frame members 32 and 34 are connected to the front and rear axles 16 and 18 by means of brackets 100 and 102.

Frame members 32 and 34 are connected to the front and rear axles 16 and 18 by means of brackets 104 and 106.

Frame members 32 and 34 are connected to the front and rear axles 16 and 18 by means of brackets 108 and 110.

Frame members 32 and 34 are connected to the front and rear axles 16 and 18 by means of brackets 112 and 114.

Frame members 32 and 34 are connected to the front and rear axles 16 and 18 by means of brackets 116 and 118.

Frame members 32 and 34 are connected to the front and rear axles 16 and 18 by means of brackets 120 and 122.

Frame members 32 and 34 are connected to the front and rear axles 16 and 18 by means of brackets 124 and 126.

Frame members 32 and 34 are connected to the front and rear axles 16 and 18 by means of brackets 128 and 130.

Frame members 32 and 34 are connected to the front and rear axles 16 and 18 by means of brackets 132 and 134.

Frame members 32 and 34 are connected to the front and rear axles 16 and 18 by means of brackets 136 and 138.

Frame members 32 and 34 are connected to the front and rear axles 16 and 18 by means of brackets 140 and 142.

Frame members 32 and 34 are connected to the front and rear axles 16 and 18 by means of brackets 144 and 146.

Frame members 32 and 34 are connected to the front and rear axles 16 and 18 by means of brackets 148 and 150.

Frame members 32 and 34 are connected to the front and rear axles 16 and 18 by means of brackets 152 and 154.

Frame members 32 and 34 are connected to the front and rear axles 16 and 18 by means of brackets 156 and 158.

Frame members 32 and 34 are connected to the front and rear axles 16 and 18 by means of brackets 160 and 162.

Frame members 32 and 34 are connected to the front and rear axles 16 and 18 by means of brackets 164 and 166.

Frame members 32 and 34 are connected to the front and rear axles 16 and 18 by means of brackets 168 and 170.

Frame members 32 and 34 are connected to the front and rear axles 16 and 18 by means of brackets 172 and 174.

Frame members 32 and 34 are connected to the front and rear axles 16 and 18 by means of brackets 176 and 178.

Frame members 32 and 34 are connected to the front and rear axles 16 and 18 by means of brackets 180 and 182.

Frame members 32 and 34 are connected to the front and rear axles 16 and 18 by means of brackets 184 and 186.

Frame members 32 and 34 are connected to the front and rear axles 16 and 18 by means of brackets 188 and 190.

Frame members 32 and 34 are connected to the front and rear axles 16 and 18 by means of brackets 192 and 194.

Frame members 32 and 34 are connected to the front and rear axles 16 and 18 by means of brackets 196 and 198.

Frame members 32 and 34 are connected to the front and rear axles 16 and 18 by means of brackets 200 and 202.

Frame members 32 and 34 are connected to the front and rear axles 16 and 18 by means of brackets 204 and 206.

Frame members 32 and 34 are connected to the front and rear axles 16 and 18 by means of brackets 208 and 210.

Frame members 32 and 34 are connected to the front and rear axles 16 and 18 by means of brackets 212 and 214.

Frame members 32 and 34 are connected to the front and rear axles 16 and 18 by means of brackets 216 and 218.

Frame members 32 and 34 are connected to the front and rear axles 16 and 18 by means of brackets 220 and 222.

Frame members 32 and 34 are connected to the front and rear axles 16 and 18 by means of brackets 224 and 226.

Frame members 32 and 34 are connected to the front and rear axles 16 and 18 by means of brackets 228 and 230.

Frame members 32 and 34 are connected to the front and rear axles 16 and 18 by means of brackets 232 and 234.

Frame members 32 and 34 are connected to the front and rear axles 16 and 18 by means of brackets 238 and 240.

Frame members 32 and 34 are connected to the front and rear axles 16 and 18 by means of brackets 242 and 244.

Frame members 32 and 34 are connected to the front and rear axles 16 and 18 by means of brackets 246 and 248.

Frame members 32 and 34 are connected to the front and rear axles 16 and 18 by means of brackets 250 and 252.

Frame members 32 and 34 are connected to the front and rear axles 16 and 18 by means of brackets 254 and 256.

Frame members 32 and 34 are connected to the front and rear axles 16 and 18 by means of brackets 258 and 260.

Frame members 32 and 34 are connected to the front and rear axles 16 and 18 by means of brackets 262 and 264.

Frame members 32 and 34 are connected to the front and rear axles 16 and 18 by means of brackets 266 and 268.

Frame members 32 and 34 are connected to the front and rear axles 16 and 18 by means of brackets 270 and 272.

Frame members 32 and 34 are connected to the front and rear axles 16 and 18 by means of brackets 274 and 276.

Frame members 32 and 34 are connected to the front and rear axles 16 and 18 by means of brackets 278 and 280.

Frame members 32 and 34 are connected to the front and rear axles 16 and 18 by means of brackets 282 and 284.

Frame members 32 and 34 are connected to the front and rear axles 16 and 18 by means of brackets 286 and 288.

Frame members 32 and 34 are connected to the front and rear axles 16 and 18 by means of brackets 290 and 292.

Frame members 32 and 34 are connected to the front and rear axles 16 and 18 by means of brackets 294 and 296.

Frame members 32 and 34 are connected to the front and rear axles 16 and 18 by means of brackets 298 and 300.

Frame members 32 and 34 are connected to the front and rear axles 16 and 18 by means of brackets 302 and 304.

Frame members 32 and 34 are connected to the front and rear axles 16 and 18 by means of brackets 306 and 308.

Frame members 32 and 34 are connected to the front and rear axles 16 and 18 by means of brackets 310 and 312.

Frame members 32 and 34 are connected to the front and rear axles 16 and 18 by means of brackets 314 and 316.

Frame members 32 and 34 are connected to the front and rear axles 16 and 18 by means of brackets 318 and 320.

Frame members 32 and 34 are connected to the front and rear axles 16 and 18 by means of brackets 322 and 324.

Frame members 32 and 34 are connected to the front and rear axles 16 and 18 by means of brackets 326 and 328.

Frame members 32 and 34 are connected to the front and rear axles 16 and 18 by means of brackets 330 and 332.

Frame members 32 and 34 are connected to the front and rear axles 16 and 18 by means of brackets 334 and 336.

Frame members 32 and 34 are connected to the front and rear axles 16 and 18 by means of brackets 338 and 340.

Frame members 32 and 34 are connected to the front and rear axles 16 and 18 by means of brackets 342 and 344.

Frame members 32 and 34 are connected to the front and rear axles 16 and 18 by means of brackets 346 and 348.

Frame members 32 and 34 are connected to the front and rear axles 16 and 18 by means of brackets 350 and 352.

Frame members 32 and 34 are connected to the front and rear axles 16 and 18 by means of brackets 354 and 356.

Frame members 32 and 34 are connected to the front and rear axles 16 and 18 by means of brackets 358 and 360.

Frame members 32 and 34 are connected to the front and rear axles 16 and 18 by means of brackets 362 and 364.

Frame members 32 and 34 are connected to the front and rear axles 16 and 18 by means of brackets 366 and 368.

Frame members 32 and 34 are connected to the front and rear axles 16 and 18 by means of brackets 370 and 372.

Frame members 32 and 34 are connected to the front and rear axles 16 and 18 by means of brackets 374 and 376.

Frame members 32 and 34 are connected to the front and rear axles 16 and 18 by means of brackets 378 and 380.

70. A spring 93 anchoring the fingers 76 to post 10 returns the fingers to latching relation with the post after each load is dumped.

As particularly shown in Fig. 1, a chain 94 anchors the quadrant 58 to rams 42, the chain passing over an idler pulley 96 carried by boom 36. It may be found desirable to bring the chain downwardly and secure it to the tractor frame instead of the ram. A cable 98 passing over a pulley 100 also carried by the boom connects quadrant 58 with the post 70. A release rope 102 fastened to latch pin 82 passes over sheave 62 and extends to a point convenient for operation by the driver of the tractor.

By varying the location of the pulley 100 and by adjusting the length of flexible member 98, it is possible to have fingers 76 maintain a substantially horizontal position throughout their upward travel. Such condition of the fingers might be preferable for loading certain materials.

Assuming for example, that the apparatus above described is to be employed for loading hay, the tractor is driven forwardly with the loader in lowered condition and with the bumper 28 pushing against depending legs 66. Hay in either loose or baled form, collects on fingers 76 and as soon as the desired load has been gathered on these fingers, the hydraulic pump 22 is caused to operate through manipulation of conventional valves provided for this purpose and comprising a part of the tractor equipment. Rams 42 thereupon raise boom 36 to elevate the load of hay. The arrangement of chain 94 and cable 98 is such that raising of the boom causes the quadrant 58 to rotate about its axis and bring legs 66 into substantially parallel relation with the boom. Simultaneously the bearing arms 68 and loading fingers 76, in fixed relation therewith, drop back to alignment with legs 66, thus raising the load to a maximum height and extending it well beyond the forward end of the tractor. A pull on the rope 102 by the operator withdraws latch pin 82 from notch 86 to permit movement of the loading fingers 76 to dumping position under action of the load carried thereon, as shown in Fig. 2. After the load is dumped, spring 93 immediately returns the loading fingers to latched engagement with post 10. Rams 42 are then returned to their normal position and the boom and loader are lowered for another load.

Much time and labor may therefore be saved with apparatus constructed as above described, and although the operation of the attachment has been explained in connection with the loading of hay, it will be obvious that this equipment may also be used for handling many other kinds of material.

If desired, the loading attachment may be removed from the boom and the remainder of the equipment used as a power crane for raising and carrying relatively large loads.

Having thus described the invention, what is claimed as new and desired to be secured by Letters Patent is:

1. In tractor-carried loading apparatus of the character described, a frame adapted for attachment to the tractor; an upright support on the frame; a boom having one end hingedly mounted on said upright; a ram having its lower end pivotally connected to the frame and its upper end pivotally connected to the boom intermediate

its ends; a loader pivotally attached to the free end of the boom, said loader comprising a section depending from the boom and a section in substantially horizontal position when the loader is in lowered condition; a hinge connecting said sections; and means operable in response to raising of said loader for moving said sections into substantially rectilinear relation to each other and to the boom.

10. 2. In tractor-carried loading apparatus of the character described, a frame adapted for attachment to the tractor; an upright support on the frame; a boom having one end hingedly mounted on said upright; a ram having its lower end pivotally mounted on the frame and its upper end pivotally connected to the boom intermediate the ends of the boom; a loader pivotally attached to the free end of the boom, said loader comprising a section hinged to the boom and depending therefrom; a second section hinged to first-named section in substantially right angular relation therewith when the loader is in lowered position means connecting the first-named section to the frame and operable in response to raising of the boom for moving said section into substantially rectilinear relation with the boom; and means interconnecting said sections and operable upon raising of the boom for moving said sections into substantially rectilinear alignment.

15. 3. In tractor-carried loading apparatus of the character described, a frame adapted for attachment to the tractor; an upright support on the frame; a boom having one end hingedly mounted on said upright; a ram having its upper and lower ends pivotally connected to the boom and frame respectively; a loader hingedly attached to the free end of the boom, said loader comprising a section hinged to the boom and depending therefrom; a second section in substantially right angular relation to the first-named section when the loader is in lowered position; a hinge joining said sections; loading fingers mounted on said hinge; latching means 40 for locking said fingers to one of said sections; means operable in response to raising of the boom for moving said sections from a right-angular to a rectilinear relation to each other and for moving said depending section into substantially rectilinear alignment with the boom to extend the loader; and means operable by a tractor operator for releasing said latching means to dump a load carried by said fingers after the loader has been raised.

45. 4. In tractor-carried loading apparatus of the character described, a frame adapted for attachment to the tractor; an upright support on the frame; a boom having one end hingedly mounted on said upright; a ram having its upper and lower ends pivotally connected to the boom and frame respectively; a loader hingedly attached to the free end of the boom; said loader comprising a pair of sections in hinged relation to each other; a quadrant fixed to one of said sections; a flexible member connecting the quadrant with the ram; the arrangement of the flexible members being such as to change the sections from a substantially right-angular to a rectilinear relation to each other as the loader is moved from a lowered to a raised position.

CURTIS C. BALDWIN.
